W. C. HIERING

BAG FASTENER

Filed May 25, 1927

UNITED STATES PATENT OFFICE.

WILLIAM C. HIERING, OF NEWARK, NEW JERSEY, ASSIGNOR TO J. E. MORGOTT CO., OF NEWARK, NEW JERSEY, A CORPORATION OF DELAWARE.

BAG FASTENER.

Application filed May 25, 1927. Serial No. 193,965.

This invention relates to devices for securing the frame sides of bags in juxtaposition and has as one of its objects to provide means for latching the securing means when in an adjusted position, the latching means being resiliently held and actuated by a hand knob.

A further feature is in the provision of a knob of artistic appearance rotatably mounted on a stem hinged to one of the frame members to tilt the stem when releasing a catch fixed on the mating frame member, in addition to its latching feature which is accomplished by partial rotation of the knob.

These and other objects, which will become apparent as the description progresses, are attained by the novel construction and combination of parts hereinafter described and shown in the annexed drawing forming part hereof, and in which:

Figure 1 is a perspective view of a conventional type of bag frame showing an application of an embodiment of the invention.

Figure 2 is an enlarged transverse sectional view of the frames and catch elements thereon.

Figure 3 is a partial longitudinal sectional view of the same.

Figure 4 is a plan view of the frame and catch element thereon with the ornamental object removed.

Figure 5 is a perspective view of the several elements in detail showing their relative position when assembled.

A common type of bag frame is illustrated in Figure 1, the same consisting of two side elements 10 and 11 of channel shaped cross section, pivoted together by rivets 12 at the ends of their angular projecting ends.

The rear side frame 11 has an elongated slot 13 in the center of its outer edge through which freely passes a flattened loop 14 formed on the enlarged circular hollow base 15 of a post 16 held normally erect as later described, the post being cylindrical and terminating in a rectangular projecting lug 17 provided with a slot 18 in its extreme end.

It is to be noted that the loop 14 extends downwardly from the base at one side thereof, so that the axis of the base is centered substantially midway of the frames, and is held tightly by the flattened portion 19 of a torsion spring 20 passed through the

bight of the loop 14 and disposed in the interior of the channel frame 11, the opposite end of the spring having an angular tang 21 pressing against the wall of the frame in a well known manner, thus allowing the post 16 to be tilted rearwardly upon the application of force, thereafter recovering its normal erect position.

Rotatably mounted on the post 16 is a knob body 22 having a hollow base 23, encircling the post base 15, and terminating in a flat plate flange 24 having flattened sides 25, resting directly on the upper surfaces of the bag frames.

Rigidly fixed on the mating side frame 10 is a stud 26 having an angular inner, rear face adapted to engage the edge of the flange 24 and base 15, causing the post and knob to tilt rearwardly until the stud has become fully entered within the chambered portion 75 of the base, whereupon the torsion spring 20 operates to move the post and knob forward and retain the lug in the chamber, holding the frame sides tightly closed.

Also rigidly secured on the frame side 10, at uniform spaced distances from the stud 26, are a pair of opposed upstanding keeper plate elements 27, having longitudinally curved or bevelled upper faces, the space between these elements being receptive of 85 the knob base 23 while the ends of plate 24 may enter undercut recesses 28 in the adjacent ends of the elements 27.

The enlarged upper portion of the knob 22 is provided with a knurled band 29 to facilitate turning by the fingers and contains an annular recess 30 having a flooring level with the upper end of the main portion of the post 16, as best seen in Figure 3.

A square block 31 having an opening 32 is fixed on the extending stem 17 of the post and impinging against one of the four flat sides of the block is the arm 33 of a spiral spring 34, the other end 35 of which is out-turned and entered in a groove in the wall 100 of the knob chamber 30, thus preventing the spring from rotating in the chamber except as the knob is turned.

Disposed over the block 31 and spring 34 is a flat disc 36 having an opening 37 through which the end of the stem 17 passes, the stem being upset thereover by spreading the notch 18 as at 38 in Figure 3.

The knob is completed by inserting an ornamental object, as the stone 39, within 110

a counterbored space 40 above the chamber 30 and spinning the thin wall 41 of the knob, above the band 29, inwardly to permanently retain the stone in place.

In operation, when it is desired to latch the bag against intrusion, the knob is turned to position the ends of the plate flange 24 within the recesses 28, as shown in Figure 1, at which time the action of the spring 34 against the side of the block 31 retains the knob in adjustment and holds the stud 26 within the chamber of the post base 23, preventing separation of the sides.

When it is required that the bag be opened, the knob is turned through an angle of ninety degrees, the spring permitting the corner of the block to pass by exerting force on the knob, and the ends of the plate flange 24 become positioned transversely of the frames to move upwardly between the ends of the keeper plates 27 when the knob and post are pressed rearwardly, thus liberating the stud and permitting the bag to open, the knob being retained in releasing position by the combined action of the spring and block until further rotated.

Although the foregoing is descriptive of the preferred embodiment of the invention, it will be apparent that minor changes may be made in its construction, without the exercise of invention.

Having thus described my invention, what I claim as new and desire to secure by Letters Patent, is:—

1. A bag fastener comprising the combination with a pair of hinged frames, of a tilt-able post mounted on one of said frames, a torsional spring in the frame to retain said post normally erect, said post having a chambered base, a stud fixed in the other frame, said stud being engageable in the chamber of said post, a knob revolvably mounted on said post, keepers fixed on the stud carried frame, and means on said knob engageable by said keepers when in one position and free therefrom when the knob is in another position.

2. A bag fastener comprising the combination with a pair of hinged frames, of a post hinged on one of said frames, means to re-

silently retain said post erect, a stud fixed on the mating frame, means in said post to engage said stud, a knob rotatable on said post, means on said post to resiliently retain said knob in an adjusted position, opposed keepers on the mating frame, and means on said knob to engage said keepers.

3. In a bag fastener having a pair of hinged frames, a post hinged on one of the frames, a knob revolvably fixed on said post, a torsion spring engaged with said post to retain it normally erect, a stud on the other frame adapted to engage said post, keepers on the last named frame, said keepers having undercut recesses, and a plate fixed on said knob to become engaged or disengaged with respect to the recesses of said keepers.

4. In a bag fastener having a pair of hinged frames, a tilttable post resiliently mounted on one of said frames, said post having a chambered base, a stud on the other frame engageable in the chambered base, a pair of undercut keepers on the last named frame, a knob completely enveloping said post, an elongated flange on the base of said knob, said flange being engageable with said keepers, a rectangular block fixed on the end of said post, and a spring fixed in said knob to impinge on the edges of said block whereby the knob is resiliently retained in adjusted position.

5. In a bag fastener having a pair of hinged frames, a tilttable post resiliently mounted on one of said frames, a stud fixed on the mating frame to engage in the base of said post when upright, a pair of keepers adjacent said stud, a chambered knob completely enveloping said post, a flange on said knob to engage said keepers, a block fixed on said post within the chamber of said knob, a spring fixed in the knob to impinge the edges of said block, a disc on said post to retain said block, spring and knob thereon, and means integral with said post for securing said disc in operative position.

This specification signed and witnessed this 12th day of May, 1927.

WILLIAM C. HIERING.
